SHARPENING DEVICE FOR SURGICAL PUNCHES

Myrle R. Peck, New York, N. Y., assignor to
American Cystoscope Makers, Inc., New York,
N. Y., a corporation of New York

Application October 29, 1936, Serial No. 108,224

5 Claims. (Cl. 51—205)

My present invention relates generally to tool sharpeners, and has particular reference to a device for sharpening surgical punches.

The type of surgical punch whose sharpening is the ultimate object of the present invention consists essentially of a cylindrical tube whose forward edge is tapered and attenuated, so that when the punch is axially advanced against a portion of tissue the sharpened edge will have a cutting effect upon the tissue. A surgical punch of this kind is used in association with an endoscopic sheath within which the punch is axially reciprocable. Means are provided at the rear end of the sheath for manually controlling the reciprocal movements of the punch, and at the forward or distal end of the sheath, there is usually provided a fenestra within which the body of tissue may be positioned so as to lie in the path of action of the punch.

The complete surgical instrument, including the sheath and accessory portions, is well known per se and is, therefore, not illustrated in the accompanying drawing.

At periodic intervals, it becomes desirable to sharpen the forward cutting edge of the punch, and it is the main object of the present invention to provide a convenient and simple device for permitting this sharpening to be effected.

A sharpening device or tool of the present character consists essentially of a tapered plug which is adapted to enter the forward end of the punch, the sharpening action being accomplished by the application of abrasive material to the plug and by rotative movements of the plug around its axis.

A feature of my invention lies in associating with the plug a means which engages snugly around the outside of the punch to assure a maintenance of the plug in axial alignment with the punch during the rotative movement of the plug.

In a preferred embodiment, the device consists of a sleeve applicable over the end of the punch, the outer end portion being constructed as a finger grip, and the plug being carried within the sleeve.

I achieve the foregoing objects, and such other objects as may hereinafter appear or be pointed out, in the manner illustratively exemplified in the accompanying drawing, wherein—

Figure 1 is a perspective view of a sharpening device of the present character, the same being about to be applied to a punch which is to be sharpened;

Figure 2 is a side view of the present sharpening device by itself;

Figure 3 is a cross-sectional view taken substantially along the line 3—3 of Figure 2;

Figure 4 is a cross-sectional view taken substantially along the line 4—4 of Figure 3; and

Figure 5 is a view similar to Figure 3, showing the punch and the sharpening device in operative association.

For the purpose of explaining the present invention, I have illustratively shown the forward portion of a punch tube 10, the same being of 10 cylindrical cross-section and having a forward cutting edge 11. In the punch illustrated, a pair of rearwardly directed prongs 12 are depicted. These prongs facilitate the removal of the punched tissue portion after the punching action 15 has been accomplished. The present invention, however, has reference only to the sharpening of the cutting edge 11.

The present device consists of a cylindrical sleeve 13 whose internal diameter is such that the sleeve may be applied endwise over the punch in a snug yet movable manner. At the outer end, the sleeve 13 is externally knurled to provide the finger grip portion 14 by means of which the sharpening device may be manipulated. This portion provides not only a convenient means for grasping the device and applying it to the punch, but also enables the user to impart rotative movements to the device.

Within the sleeve 13 I provide a tapered plug 15, preferably formed on the rear end of an element 16 which is permanently secured within the outer portion of the sleeve 13. The taper on the plug 15 conforms exactly with the taper which the forward portion of the punch should embody.

At the midportion of the sleeve 13 I provide a pair of opposed apertures 16 through which the plug 15 is visible, and through which abrasive material may be applied to the plug.

The sleeve 13 is composed of any convenient material, preferably nickel-plated metal, and the plug 15 is preferably composed of metal having adequate hardness for the contemplated purpose.

When the present device is to be used, the punch is first separated from the other portions of the surgical instrument of which it forms a part. The present tool is then applied over the end of the punch until the parts assume the relationship shown most clearly in Figure 5. Abrasive material is then applied through the apertures 16 onto the plug 15, and rotative movements are imparted to the plug. This is accomplished by holding the punch in one hand and by grasping the finger grip portion 14 with the other hand;

then twirling the sharpening device with respect to the punch. At the same time, a certain amount of pressure is exerted to maintain the plug and the punch in adequate rubbing contact. The 5 device is simple enough to permit it to be withdrawn from the punch with great ease, so that the effect of the sharpening action may be periodically inspected. When the punch is completely sharpened, it may be readily cleaned, sterilized, and set aside for subsequent use. Similarly, the present tool may be cleaned or wiped off and laid aside until it is again required.

The forward portion of the sleeve 13 is an important feature of the present construction, because it snugly engages around the punch during the time that the plug is in rubbing action with the cutting edge of the punch. This assures a maintenance of the plug in accurate axial alignment with the punch during the sharpening action.

In general, it will be understood that changes in the details, herein described and illustrated for the purpose of explaining the nature of my invention, may be made by those skilled in the art without departing from the spirit and scope of the invention as expressed in the appended claims. It is, therefore, intended that these details be interpreted as illustrative, and not in a limiting sense.

Having thus described my invention, and illustrated its use, what I claim as new and desire to secure by Letters Patent is—

1. A sharpening device for a cylindrical surgical punch, comprising a cylindrical sleeve snugly applicable over the end of the punch, and a tapered plug carried within the sleeve and adapted to enter into the punch.

2. A sharpening device for a cylindrical surgical punch, comprising a cylindrical sleeve snugly applicable over the end of the punch, and a tapered plug carried within the sleeve and adapted to enter into the punch, the outer end portion of the sleeve being constructed as a finger grip portion to permit rotation of the plug within the punch.

3. A sharpening device for a cylindrical surgical punch, comprising a cylindrical sleeve snugly applicable over the end of the punch, and a tapered plug carried within the sleeve and adapted to enter into the punch, the outer end portion of the sleeve being constructed as a finger grip portion to permit rotation of the plug within the punch, the midportion of the sleeve having an aperture to permit introduction of abrasive material to the plug.

4. A sharpening device for a cylindrical surgical punch, comprising a tapered plug insertable into the end of the punch, a finger grip enabling rotative movement of the plug around its axis, and means carried by the plug and adapted to engage snugly around the punch to maintain the plug in axial alignment with the punch during said rotative movement.

5. A sharpening device for a cylindrical surgical punch, comprising a tapered plug insertable into the end of the punch, and a cylindrical sleeve carried by the plug and adapted to engage snugly around the punch when the plug is inserted, whereby the plug upon rotation may be maintained in axial alignment with the punch.
